Application August 10, 1945, Serial No. 610,179

5 Claims. (Cl. 250—33.67)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to electrical apparatus and more particularly to directional radio antennas.

Conventional loop antennas are known to have directional receiving properties, that is, the signal supplied to a receiver by the antenna is a maximum when the source of received signals lies in the plane of the loop, and the signal supplied by the antenna is a minimum when the axis of the loop is directed at the source of the received signals. It is also known that the usefulness of the conventional loop antenna is limited by the fact that the receiving sensitivity pattern of the antenna is symmetrical about both the plane of the loop and the axis of the loop and that two no-signal or null points exist in the receiving pattern. When loop antenna is directed so that the signal is reduced to zero or a minimum, it is then known that the source of the received signal lies along the axis of the loop, but it is impossible to tell on which side of the loop the station lies.

Combinations of the conventional loop antenna with other directional and nondirectional antennas have been used to determine the true location of the signal source. These combinations usually require the mixing of the signals from two or more antennas with the consequent complexity of circuits involved. The accuracy of these systems also depends to a large degree on the careful adjustment of the circuits and the proper proportioning of the signal strengths of the various antennas.

It is an object of the present invention, therefore, to provide a loop antenna, hereinafter called the "Carter-loop antenna," that has a single no-signal or null point in the complete 360-degree field pattern about the antenna.

It is a further object of this invention to provide means including a single loop antenna and associated receiver circuit for locating a source of radio-frequency signals.

For a better understanding of the invention, together with other and further objects thereof, reference is had to the following description taken in connection with the accompanying drawings in which:

Fig. 1 is a sectional view of a conventional loop antenna;

Fig. 2 is the directional receiving pattern of the antenna of Fig. 1;

Fig. 3 is a sectional view of the present invention;

Fig. 4 is a front view of the invention;

Fig. 5 is a directional receiving pattern afforded by the present invention; and

Fig. 6 is a schematic view showing one application of the present invention.

The disadvantages of conventional loop antennas may be more fully understood by considering Figs. 1 and 2. The loop antenna 8 of Fig. 1 consists of a form 10 on which a continuous conductor is wound in several turns forming one or more uniform layers. In this example a single layer of turns 12 is shown. The two ends of the conductor that is wound on form 10 are connected through a shielded cable 14 to a receiver (not shown). The amplitude of the signal supplied by this antenna to the receiver as a function of angular position is illustrated in Fig. 2. A plan view of antenna 8 is shown as a reference. The distance from the center point 16 of antenna 8 to the two curves 18 and 20 is proportional to the intensity of signal supplied by antenna 8 to the receiver as a unit signal source is moved in a circle about point 16, the distance in all cases being measured in the direction of the signal source. It can be seen from Fig. 2 that two no-signal or null points exist when the signal source is in the directions indicated by lines 22 and 24. Lines 22 and 24 are coincident with the axis of the turns wound on form 10. This axis is hereinafter called the "loop axis." If antenna 8 is employed in the normal manner, that is, is rotated about a vertical axis passing through point 16 to locate a fixed source of signals, it would be impossible to determine whether the source of the signal came from the direction of line 22 or line 24.

Referring now to Fig. 3 where there is shown a sectional view of a one-null or Carter-loop antenna 30, the structure includes a dielectric or plastic form 32 identical with or similar to the form 10 shown in Fig. 1. The windings 34 on form 32 are formed from a single conductor but the turns are not wound in uniform layers as was the case in Fig. 1; rather they are wound in the form of a so-called banked winding. In this case the left edge of the winding 34 consists of only a single layer of turns while near the right edge winding 34 consists of four layers of turns. Each turn of the winding is insulated from all other turns by employing enameled covered wire or by placing some form of insulating material between adjacent turns. In this embodiment of the invention the first alternative is

chosen. The number of layers is not limited to the number set forth above nor should the above numbers be taken as typical of any type of antenna, rather they should be interpreted as illustrating the principle upon which this invention is based. The two ends of the conductor that make up the winding 34 are connected through shielded cable 36 to a receiver 38.

Fig. 4 shows a front view of antenna 30, cable 36 and receiver 38 being schematically shown as before. Parts in Fig. 4 are numbered to correspond with like parts in Fig. 3.

The directional receiving properties of this invention are illustrated by Fig. 5. In Fig. 5 the distance from the center point 42 of antenna 30 to curve 48 is proportional to the intensity of signal supplied to receiver 38 by antenna 30 when a constant signal source is moved in a circle about point 42, the distance being measured at all times in the direction of the signal source.

It can be seen that curve 48 dips very sharply in the direction of line 46, line 46 lying along the loop axis of antenna 30. A slight decrease in signal occurs in the direction of line 48 which also lies along the loop axis of antenna 30, but this slight decrease in signal may be easily differentiated from the decrease in signal in the direction of line 46. The nonsymmetrical receiving sensitivity pattern is due to the fact that the antenna supplies a much stronger signal to the receiver when the banked side of the winding is nearer the signal source than is supplied when the low side of the winding (in this example the side having only a single layer of turns) is nearer the signal source. Line 46 therefore lies on the banked side of winding 34.

The use of this antenna as a direction finder is apparent from a study of the above description. Antenna 30 is mounted so that it may be rotated about a vertical axis passing through point 42 and perpendicular to the loop axis of the antenna. When a signal is received, antenna 30 is rotated about this vertical axis until a very sharp decrease in signal occurs. When the antenna is rotated to the no-signal position, the source of received signals will lie on the line that is a prolongation of the loop axis of the antenna and on the side of the antenna that has the most layers in the winding.

An application of this antenna is shown in Fig. 6. An airplane 60 equipped with a Carter-loop antenna 62 receives signals from a radio transmitter 64. The antenna 62 on airplane 60 is now rotated to the no-signal position. The station 64 is identified by the radio operator in airplane 60, and a line of position from the known location of the station to airplane 60 is established. The airplane 60 may "home" on station 64 or a line of position to a second station (not shown) may

be established so that the operator in airplane 60 may locate his position by triangulation. Obviously the example given above is only one of many applications of this invention.

While there has been described what is at present considered the preferred embodiment of the invention, it will be obvious to those skilled in the art that various changes and modifications may be made therein without departing from the invention.

What is claimed is:

1. In combination with a receiver, a directional antenna comprising a dielectric supporting means, a continuous conductor having a first portion helically wound in a plurality of turns on said supporting means and a second portion coaxially wound on said first portion in a plurality of turns forming a plurality of layers banked at one end of said supporting means, each of said turns being electrically insulated from the others, and a shielded cable connecting the ends of said conductor to said receiver.

2. In combination with a receiver, a directional antenna comprising a dielectric supporting means, a continuous conductor having a first portion wound in a plurality of turns on said supporting means, and a second portion wound on said first portion in a plurality of turns forming banked layers at one end of said supporting means, and a shielded cable connecting the ends of said conductor to said receiver.

3. In combination with a receiver, a directional antenna comprising a continuous conductor having a first portion wound in a plurality of turns forming a helix and a second portion wound on said first portion in a plurality of turns forming a plurality of banked layers at one end of said helix, and a shielded cable connecting the ends of said conductor to said receiver.

4. A directional antenna comprising a continuous conductor having a first portion wound in a plurality of turns forming a helix and a second portion wound on said first portion in a plurality of turns forming layers unequally distributed along said first portion to provide for sense determination of the source of energy induced in said antenna.

5. A directional antenna as set forth in claim 4, wherein the layers are banked.
